 ELECTROLYTIC PROCESS FOR PRODUCING
DIHYDROXYCAPRONITRILE

Robert W. Foreman, Chagrin Falls, Ohio, assignor to
The Standard Oil Company, Cleveland, Ohio, a corpora-
tion of Ohio
No Drawing. Filed Feb. 3, 1964, Ser. No. 342,264
12 Claims. (Cl. 204—77)

The present invention relates to a process for the production of dihydroxycapronitrile by the hydrolysis of dihydrocyanopyran to glutaraldehyde monocyanhydrin and the reduction of glutaraldehyde monocyanhydrin to dihydroxycapronitrile.

In the present invention 3,4-dihydro-2-cyano-2H-pyran or sometimes referred to herein simply as dihydrocyanopyran, which can be prepared from acrolein and acrylonitrile as described in my copending U.S. patent application, Ser. No. 251,056, filed Jan. 14, 1963, now Patent No. 3,153,052, is hydrolyzed in an aqueous solution of an acid salt to the monocyanhydrin of glutaraldehyde which is then reduced to 2,5-dihydroxycapronitrile in an electrochemical reaction by the following steps:

Step I

Step II

The hydrolysis reaction may be carried out in a dilute aqueous solution of an acid, an acid salt or in the presence of a cation exchange material. The acid, acid salt or cation exchange material is a catalyst and is not consumed in the reaction. Preferably a dilute aqueous solution of an acid sulfate is utilized which later also may serve as the electrolyte in the electrolytic reduction step of the process. Such an electrolyte can be recycled after removal of the dihydroxycapronitrile, thereby simplifying the process and reducing the consumption of acidic catalyst.

The electrolytic reduction of the glutaraldehyde monocyanhydrin may be conveniently carried out in an undivided cell, using preferably, a lead cathode and a lead dioxide or platinum anode. If a divider is used to separate the cathode and anode compartments, a permselective cation exchange membrane is preferred. The monocyanhydrin of glutaraldehyde is fed to the cathode compartment and the product, dihydroxycapronitrile, may be recovered from the aqueous catholyte by means of solvent extraction. The electrolyte can then be recycled to the hydrolysis reaction or to the electrolytic cells as desired. Selective catalytic hydrogenation of the aldehyde group of the monocyanhydrin of glutaraldehyde is difficult. With Raney nickel, for instance, high temperatures and pressures are required to catalyze the hydrogenation, and then the nitrile group is hydrogenated in preference to the aldehyde group. Unexpectedly, the most successful means for the conversion is by electrolytic reduction.

The hydrolysis Step I and the electrochemical reduction Step II may be conducted in separate or the same reaction vessels in a sequential or simultaneous manner and still be within the scope of the present invention. If the two steps are carried out simultaneously, however, reac-

2

tion conditions must be adjusted to maximize the yields in both reactions.

As shown by equation earlier, the product of the hydrolyzed dihydrocyanopyran (Step I) exists as an equilibrium mixture of the aldehyde, monocyanhydrin, and the cyclic hydroxy compound, 2-cyano-6-hydroxytetrahydropyran. It is believed that the aldehyde form is selectively reduced in Step II thus shifting the equilibrium away from the cyclic hydroxy compound.

10 In the hydrolysis Step I any water soluble acidic material having an acid strength equal to or greater than that of acetic acid ($K=1.75 \times 10^{-5}$) is suitable as a catalyst. Acidic catalysts useful in the reaction of this invention include, but are not limited to, sulfuric acid, hydrochloric acid, other halogen acids, phosphoric acid; acid salts such as ammonium bisulfate, sodium bisulfate, sodium acid phosphate, and the like. Cation exchange resins in their acid forms such as sulfonated styrene-divinyl benzene copolymers may also be used and such materials include 15 20 Amberlyst-15, Dowex-50, Amberlyte-400, IR-20 and the like. Ammonium bisulfate is the preferred hydrolysis catalyst in the instant invention.

The rate of hydrolysis of dihydrocyanopyran to glutaraldehyde monocyanhydrin depends upon temperature 25 and degree of acidity. The higher the temperature and the greater the acidity, the shorter the time required for reaction to a given conversion. For instance, at 90° C. a minimum of 0.05 N strong mineral acid, such as sulfuric, is required in order to achieve hydrolysis in a reasonable length of time, whereas at room temperature an acidity of 2.0 N strong acid is necessary for practical hydrolysis rates. With 5 or 6 N strong acid, hydrolysis is completed in a matter of a few minutes. The preferred reaction temperatures range from about room temperature 30 to 100° C. or slightly higher. Preferably dihydrocyanopyran is fed to the hydrolysis reaction mixture in proportions such that the resulting monocyanhydrin of glutaraldehyde is soluble in the reaction medium and for an aqueous acid medium this is generally about 30—40% by 40 weight.

Although either a divided or an undivided cell may be used in the electrolytic reduction step, there is some preference for the use of a divided cell because some dihydroxycapric acid forms in the undivided cell by anodic hydrolysis of the nitrile group. The dihydroxycapric acid will probably impede dihydroxycapronitrile formation and crystallization. It is estimated that approximately one-third of the dihydroxycapronitrile produced by electrolysis in an undivided cell is hydrolyzed to the hydroxy acid. 45 If the membrane is used to separate the reactions at the anode and the cathode, it is preferred that a cationic permselective ion exchange resin be utilized. Any commercially available permselective cationic membrane such as Permutit 3142 or AMF-ion C102 would be suitable.

50 The preferred cathode composition is lead. Actually, the cathode material may be any conductive material that is passive under the influence of the cathode voltage as for example, cadmium, mercury, steel, iron, nickel and the like. Material selected for the anode must be resistant to the action of strong acids under anodic oxygen. 55 Preferably the anode is composed of lead dioxide or platinum.

55 For a more simplified and economical operation, the same acid medium that is employed in the hydrolysis may also be employed as the electrolyte. Again ammonium bisulfate is preferred. The concentration of the acid in the electrolyte solution is controlled by three factors. Sufficient acid must be present to provide conductivity and to aid solubilization of the monocyanhydrin of glutaraldehyde in the electrolyte at practical levels, e.g., in amounts of about 1 to 3 moles. The loss of excess acid 60 in the separation of dihydroxycapronitrile from the reac-

tion medium should be minimized. If dihydroxycapronitrile is recovered by means of an immiscible solvent, the use of excess acid will tend to solubilize the solvent. It is therefore preferred that the acidity of the electrolyte be in the range equivalent to from about 0.05 moles of sulfuric acid per liter or a normality of 0.1 up to 10 moles of sulfuric acid per liter or a normality of 20.

The electrolytic reduction is usually carried out at temperatures ranging from about room temperature to about 45° C. However, temperatures of from 20° C. to 60° C. are operable.

The current densities in the electrolytic cell may vary widely. Generally the current density should fall within a range of 5 to 100 amps per square foot and a range of 20 to 50 amps per square foot is preferred. Theoretically, at least two Faradays of electricity are required to reduce one mole of the monocyanhydrin of glutaraldehyde to one mole of dihydroxycapronitrile.

The dihydroxycapronitrile produced by the present process is a known compound which is useful in some cases as a solvent and also as an intermediate glycol material in the preparation of alkyd resins by condensation with a dibasic organic acid or its anhydride.

The present invention is further illustrated in the following examples wherein the amounts of ingredients are expressed as parts by weight unless otherwise indicated.

EXAMPLE I

Step I reactions employing various acids and acid salts at varying concentrations and reaction conditions are illustrated in detail in Table I. In each case the conversion of dihydrocyanopyran to the equilibrium mixture of the monocyanhydrin of glutaraldehyde and the tetrahydroxycyanopyran was complete.

The hydrolysis of dihydrocyanopyran was conducted either in a mechanically stirred flask or the agitation was supplied by shaking the reaction flask. Water bath heating was used until the visible dissolution of dihydrocyanopyran occurred and then the hydrolysis continued for about 10 to 30 minutes thereafter. When Amberlyst resin was used, it was converted to the acid form and then washed with water prior to use in the hydrolysis reaction. 20 grams of resin per 100 ml. of water and 0.1 mole of dihydrocyanopyran were used. The monocyanhydrin of glutaraldehyde was isolated by neutralizing the

hydrolyzed product with sodium carbonate containing some sodium sulfate or sodium chloride followed by extraction with ether. The ether was then removed carefully from the hydrolysis product at near room temperature and under nitrogen.

The analytical determination of the monocyanhydrin of glutaraldehyde was carried out by adding excess hydroxylamine hydrochloride solution to an appropriately sized sample. Reaction of the aldehyde with hydroxylamine caused the liberation of hydrogen chloride which was determined by titration with standard base. The Amberlyst 15 resin appearing in Table I is a sulfonated copolymer of styrene and divinyl benzene.

EXAMPLE II

The electrolytic reduction Step II is illustrated in this example. Two different electrolysis cells were used in conducting the experiments. One cell consisted of two, three-inch diameter cylindrical plastic sections 1½" thick and ¾" thick sandwiched together with disc electrodes at each end. A semipermeable sulfonated styrene-divinyl benzene copolymer membrane supported on a polyester web (Permutit 3142) was sandwiched between using rubber gaskets for sealing. The entire assembly was held together in an insulated wood vise. A mechanically driven angular glass rod provided stirring in the larger compartment which served as the cathode chamber. Electrical connections were made by clips to ears on the electrodes. A six-volt adjustable D.C. power supply and suitable volt meter and ammeter were also in the circuit.

The second cell was designed so that many cells could be stacked together in a minimum space. Flow-through provided stirring, and cell circuitry was the same as for the cell described above. In operating either cell, the electrolyte was charged to both chambers simultaneously. The monocyanhydrin of glutaraldehyde was added either gradually to the catholyte or was present initially. Experiments were conducted and remained at current and voltages where little or no cathode gassing took place. The experiments were continued to a predetermined Faraday/monocyanhydrin of glutaraldehyde ratio. In the second cell, circulation to and from the reservoir occurred at such a rate that the cell residence time was approximately 30 seconds. The circulation was on the order of 300 cc. per minute.

¹ Dihydrocyanopyran.

² Conversions were 100% in each example.

³ Not determined.

Experimental examples showing the feasibility of a number of different electrodes, electrolytes, and reaction conditions are summarized in Table II. The analysis of unreacted monocyanhydrin of glutaraldehyde and dihydroxy-capronitrile was made as the electrolysis proceeded. The analytical procedure for the determination of dihydroxy-capronitrile included adding an excess of 0.1 normal silver nitrate to a suitable size sample, adjusting the pH with caustic to 7.5 until the pH remained at that level for a minimum of five minutes. The silver cyanide produced was removed by filtration, the pH was adjusted to the acid side with dilute nitric acid, and the excess silver ion was determined by titration with standard potassium thiocyanate to a ferric alum end point. If too much sulfate was present in the sample, it was removed as barium sulfate before proceeding with the analysis.

In Table II the Faraday-to-mole monocyanhydrin of glutaraldehyde ratio was slightly greater than 2. The conversions varied from about 69 to 100%.

4. The process of claim 3 wherein the hydrolysis is carried out at a temperature in the range of from about room temperature to slightly above 100° C.

5. The process of claim 4 wherein the electrolytic reduction is carried out at a temperature in the range of from about 20 to 60° C.

6. The process of claim 5 wherein the electrolytic reduction is carried out at a current density of from 5 to 100 amps. per square foot.

10 7. The process of claim 6 wherein the acid catalyst is present in a concentration of from 0.5 N to 20 N.

15 8. The process of claim 7 wherein the acid catalyst is a member selected from the group consisting of sulfuric acid, hydrochloric acid, other halogen acids, phosphoric acid, sodium bisulfate, ammonium bisulfate, sodium acid phosphate, and cation exchange resins in the acid form.

9. The process of claim 8 wherein the acid catalyst is hydrochloric acid.

¹ Monocyanhydrin of Glutaraldehyde. ² Dihydrocyanopyran.

I claim:

1. The process for the manufacture of 2,5-dihydroxy-capronitrile comprising hydrolyzing 3,4-dihydro-2-cyano-2H-pyran in an aqueous medium in the presence of an acid catalyst to form the monocyanhydrin of glutaraldehyde and electrolytically reducing the monocyanhydrin of glutaraldehyde in an aqueous medium in the presence of an electrolyte to 2,5-dihydroxycapronitrile.

2. The process of claim 1 wherein the acid catalyst is a material which has an acidity of at least $K = 1.75 \times 10^{-5}$.

3. The process of claim 2 wherein the electrolyte is the same as the acid catalyst.

45 10. The process of claim 8 wherein the acid catalyst is sulfuric acid.

11. The process of claim 8 wherein the acid catalyst is sodium bisulfate.

12. The process of claim 8 wherein the acid catalyst is a cation exchange resin in the acid form.
